UNITED STATES PATENT OFFICE.

EMMA R. KNUDSON, OF JEWELL, IOWA.

LAUNDRY CLOTHES-HANDLING APPARATUS.

Application filed January 19, 1926. Serial No. 82,349.

The invention provides simple and effective means for handling clothes during the washing, or laundering process without subjecting the person to the liability of being burned when placing the articles in the boiler, or when removing them from the boiler and transferring the articles to a tub, or launder in the final process.

While the drawings illustrate a preferred embodiment of the invention, it is to be understood that in adapting the means to meet specific needs and requirements, the design may be varied and such other changes in the minor details of construction may be resorted to within the scope of the invention, as claimed, without departing from the spirit thereof.

For a full understanding of the invention and the merits thereof, reference is to be had to the following description and the drawings hereto attached, in which—

Figure 1 is a plan view of the sling, the bails being extended and one of the bails having its intermediate portions broken away,

Figure 2 is an enlarged detail sectional view on the line 2—2 of Figure 1, and

Figure 3 is a detail sectional view of a wash boiler with the sling in position thereon and supporting the articles to be boiled.

Corresponding and like parts are referred to in the following description and designated in the several views of the drawings by like reference characters.

The sling comprises a body member and oppositely disposed bails, or V-shaped arms 18 which are pivoted to the body member and which are provided at their outer or free ends with loops 19 to engage the hook ends of the parts 9. The loops 19 are coiled about the free ends of the bails 18 and the latter are of a length to project above the sides of the wash boiler 20, so that the loops 19 may be swung outwardly to be out of the way and to be conveniently engaged with the hooks 9. The body of the sling comprises a metal frame 21 which conforms to the inner contour of the wash boiler, so as to obtain a snug fit therein. A wire fabric 22 is stretched over the frame 21 to receive and support the clothing, or other articles to be laundered. A metal binding 23 is fitted about the frame 21 and an edge portion is connected to the marginal edge of the wire fabric 22 by means of a lap joint, as shown

most clearly at 24 in Figure 2. The body member is reinforced by longitudinal and transverse metal straps 25, the ends of which are bent about the frame of the body. The transverse straps 25 have their end portions bent to engage about the inturned ends 26 of the bails 18, as shown most clearly in Figure 2.

In the operation of the invention the clothing, or articles to be laundered are placed upon the sling and are transported thereby to the wash boiler 20 and are lowered therein, as indicated in Figure 3. After the clothing has been boiled a sufficient time to loosen the dirt, the sling with the clothing thereon is lifted from the wash boiler 20 by means of the loops 19 and may be held suspended for a short time to permit the surplus suds water to drain into the boiler. After the clothing has drained sufficiently, it is transferred to the tub, or other receptacle in the next step. Upon releasing one of the bails, or arms 18 and lifting the sling by the other arm the clothing is readily discharged into the receptacle, as will be readily comprehended.

Having thus described the invention, I claim:

1. In apparatus of the character specified, a sling comprising a frame, a wire fabric covering the frame and secured at its marginal edge thereto, metal straps extending beneath the wire fabric from one side of the frame to the other and attached at their respective ends to the frame at opposite points, and arms pivotally connected to the frame by said straps which are bent around the frame and the pivotal ends of the arms.

2. In apparatus of the character specified, a sling comprising a frame, a wire fabric covering the frame, a binding applied to the frame and having an edge portion connected to the wire fabric by means of a lap joint, metal straps reinforcing the wire fabric and having their ends bent about the said frame and binding, and bails applied to opposite sides of the sling and having their ends offset laterally and connected to the frame by the metal straps which are bent therearound.

In testimony whereof I affix my signature.

EMMA R. KNUDSON. [L.S.]
